UNITED STATES PATENT OFFICE

FREDERICK KRUEGER, OF HUNTINGTON, NEW YORK

DESIGN FOR A DUTCH MILL SHOP

Application filed May 8, 1930. Serial No. 35,543. Term of patent 7 years.

To all whom it may concern:

Be it known that I, FREDERICK KRUEGER, a citizen of the United States, residing at Huntington, in the county of Suffolk and State of New York, have invented a new, original, and ornamental Design for Dutch Mill Shop, of which the following is a specification, reference being had to the accompanying drawings, forming part thereof.

Fig. 1 is an end elevation of a Dutch mill shop showing my new design.

Fig. 2 is a front perspective.

I claim:

The ornamental design for a Dutch mill shop, as shown.

FREDERICK KRUEGER.
